UNITED STATES PATENT OFFICE

DAVID H. HAYDEN, OF BROOKLYN, NEW YORK

FORM

Application filed May 10, 1924. Serial No. 712,210.

My invention relates to an improvement in forms for concrete, and one of the objects thereof is the provision of an improved construction in this art whereby much of the delay incidental to this type of work as now performed is eliminated, my improved construction permitting the concrete work to keep abreast of the steel work.

A further object of my invention is the provision of an improved construction whereby not only may the forms be constructed as the steel work proceeds, but the wrecking of the forms after the concrete has been poured may be accomplished with the minimum amount of labor and in the minimum time.

A further object of my invention is the provision of a construction of the character above indicated wherein light timbers only are required, thus not only reducing the cost so far as the materials themselves are concerned, but also reducing the labor cost as applied both to erecting and wrecking.

In all of the various methods now employed in this kind of work the construction of the molds or forms enclosing the girders is the slow part of the work, but in my improved construction this portion of the work may proceed rapidly, my improved apparatus being of such a character that the girder construction may be installed in the whole building, if desired, before installation of the panels or bays.

A further object of my invention is the provision of girder form construction and panel decking so constructed and arranged that loading the panels at one side of the girder forms will not affect the other side.

A still further object of my invention is the provision of a form structure in which the girder forms bounding the panel are independently suspended intermediate their ends, braces being provided for preventing relative movement between the forms, thereby eliminating in a practical way swaying of the forms or relative movement of the component parts of the forms.

A still further object of my invention is the provision of a form structure in which the panel deck structure is supported mainly by the girder forms, thereby eliminating to

a very considerable degree the numerous supporting posts which are employed under the present practice for supporting the deck structure.

Another object of the invention is the provision of an improved form construction wherein the forms may be built in tiers without waiting until the concrete has been poured at each floor. In other words, it is unnecessary to wait until the work at one floor has been completed before proceeding with the erection of the forms at the next floor.

Further objects of my invention will appear hereinafter.

In the accompanying drawings I have shown my improved construction in its various stages:

Figure 1 is a perspective view showing part of one of the girder forms and the devices for supporting and bracing the forms.

Fig. 2 is a section on the line 2—2 of Fig. 1;

Fig. 3 shows in detail the hangers employed in suspending the girder forms;

Fig. 4 is a detail of the girder forms;

Fig. 5 is a somewhat enlarged view of the girder forms showing the end of one of the form girders in place;

Fig. 6 is a plan view of the panel or bay with part of the floor or deck thereof in place;

Fig. 7 shows the supporting posts in place and the means for leveling the panel;

Fig. 8 is a section on the line 8—8 of Fig. 6;

Fig. 9 is a view after the concrete has been poured and showing the shock post in place;

Fig. 10 shows a modified method of adjusting the supporting posts, this form being of advantage when the forms are built in tiers; and

Fig. 11 is a further modification of the supporting posts.

Referring to the drawings in detail, 1 and 2 designate columns which are spanned by a girder 3. 4 and 5 designate two other girders which it will be understood extend from the columns 1 and 2 to two other columns which are not shown, these last two columns being spanned by a fourth girder.

The girder forms for these four girders, of

course, constitute the boundaries of the panel or bay.

Each column is provided with a collar or clamp, which I have designated 6 and 7. These clamps may be of any suitable type and are applied directly to the column.

Suspending from the girders intermediate their ends are metal hangers 8 carrying diagonals 9. The hangers, as illustrated, have a loop in their lower ends in which is hooked a member 10, this member extending down between a pair of diagonals 9, each diagonal, so to speak, comprising two members, and the lower end of the member 10, is provided with a loop 11 in which I insert a piece of wood or other suitable material, designated 12, which will lie underneath the diagonals 9. In this fashion the diagonals, it will be seen, will be suspended from the girders. It is to be noted that the hangers 8 are in pairs and that one is hooked over the girder from one side while the other is applied from the opposite side.

The girder forms comprise soffit members 13, in sections, if desired, the joint between the adjacent ends of the soffits falling on the diagonals 9. The side members or haunches 14 and 15 of the girder forms have their ends resting on and supported by the column clamps or supports 6, as illustrated in the drawings, and these members are also preferably sectional for convenience in handling, the joint between the adjacent ends of the sections falling on the diagonals 9.

As so far described, it will be seen, therefore, that my improved construction is made up of what is known as "one-man pieces", which allows the construction to be easily installed and just as easily wrecked after the concrete has been poured. It will be seen also that the girder forms are individually suspended intermediate their ends. I wish to mention also at this point that they may be suspended at their ends also, if desired.

In order that the adjacent girder forms may be held against relative movement I provide braces 16 which are nailed to the diagonals 9, as plainly indicated in Figs. 1 and 6. These braces also provide a rigid structure so far as the girder forms are concerned.

Two opposed sides of the bay or panel are provided with straight battened haunches, as shown in Fig. 4, the battens being designated 17. A ledger 18 is nailed to the outside of these battens and is provided for the purpose of forming a support for the joists 19 of the panel deck. The other two opposed haunches of the bay are not provided with ledgers 18, preferably, but are provided with stirrups 20, these stirrups supporting the deck girders 21. It is to be understood that other means for supporting these form girders may be provided, if desired. As a matter of fact, two battens similar to the bat-

tens 17 could be applied to these haunches about six inches apart and a ledger member could span these battens. The stirrup, however, is perhaps a more convenient arrangement.

I have heretofore mentioned that the diagonals 9 and the braces 16 are in separate pieces. It is to be understood, however, that these members may be in one piece, if desired. I prefer the arrangement illustrated, however, inasmuch as the girders are not always of the same depth.

The panel deck structure is in the main supported by the girder forms. This deck structure is clearly illustrated in Figs. 6 and 7. In installing this structure I erect a group of supporting posts at the center of the deck, four posts having been employed in the present instance and designated 22, 23, 24 and 25. The posts 22 and 23 are connected to each other close to the floor by a stay lath 26, while the posts 24 and 25 are connected to each other by a stay lath 27. These stay laths are nailed to the posts and are provided for the purpose of tying the bottoms of the posts together.

The tops of the posts are connected by means of a cap member or plate. I have designated these members 28 and 29, and they lie between the tops of the posts and the underside of the form girders. At a convenient height from the floor to form a scaffold I attach stay laths 30 and 31 to the supporting posts and the workmen may install a part of the panel deck standing on these scaffolds. The deck girders 21 are preferably in sections for convenience in handling, the adjacent ends of these sections resting on the cap plates 28 and 29 immediately above the supporting posts. The joists 19 are set diagonally to accommodate the deck boards 34, this diagonal setting of the joists enabling the abutting ends of two boards to be conveniently nailed to the same joist.

The bay or panel may be levelled by inserting wedges 35 and 36 beneath the foot of each post, these wedges being driven in until the panel is levelled.

After the concrete is poured and before the beginning of the wrecking operation I insert a shock post 37 beneath the panel, this post, as will be apparent from the drawings, bearing against the underside of one of the deck boards 34. This post can be left in place as long as desired after the rest of the construction has been wrecked. The purpose of the shock post is to take care of careless loading of the concrete slabs before the slabs have properly set. These posts are small and consequently will not interfere with other trades working on the job before the posts are removed. Wedges 38 are driven beneath the foot of the shock post or between the top of the post and the deck board, as desired, until

the post is brought into proper contact with the slab.

In wrecking my improved forms the wedges 35 and 36 are removed from beneath their respective posts. The stay laths 26 and 27 may be then removed and the posts themselves removed by attaching a rope or other convenient device thereto. The deck materials will then fall to the floor and inasmuch as they are in short sections the floor will not be damaged. The girder forms may then be removed by simply removing the diagonals 9 and the column supports or clamps 6, leaving the haunches and soffits supported by the adhesion between the concrete and the wood. These members may then be removed by pinch bars or other convenient tool. The hangers 8 by which the girder forms are suspended from the girders are left in place enclosed in the concrete, the hooks 10 only being removed. These hooks may be readily removed by simply working them loose from the concrete and then unhooking them from the hangers.

As I have pointed out hereinbefore, my improved construction may be built up in tier formation, one set of forms being built or superimposed upon the other. This is indicated in Fig. 10. I might say at this point, however, that in constructing my forms at different floor levels the supporting posts 22, 23, 24 and 25 at one floor level are placed immediately above corresponding posts on the level below. If desired, posts similar to the posts 22, 23, 24 and 25 may be employed in building up the tier formation, but I prefer to employ a form of post such as illustrated in Fig. 10 or in Fig. 11. Referring to Fig. 11, it will be seen that the post there designated 22' is shorter than the corresponding post 22. To lengthen the post to the desired length I insert a block of wood 39 attached to the foot of the post by cripes 40. A plate 41 rests on the panel deck of the floor below and immediately above the top of the supporting post on that floor. The block 39 carries a bolt 42 and washer nut 43. The post 22' and block 39 rest on the washer nut and the lower end of the bolt, which is slightly pointed, rests in a hole in the plate 41. When this type of supporting post is employed the panel may be levelled by driving wedges between the tops of these posts and the cap plate, as indicated on the drawing. These forms may be built up any number of stories desired without regard to whether the concrete has been poured or not. When the concrete is poured, of course, the plate 41 will be covered over but is easily removed when the deck board on which it rests is removed. When this type of supporting post is employed and is placed before the concrete is poured, the same may be readily removed after the concrete is in place by merely removing the wedges at the top of the post, removing the cripes 40, and then pulling

the post out, after which the bolt and its washer may also be removed, the plate, as just stated, being removed after the deck board on which it rests is wrecked.

In Fig. 11 I have shown another form of supporting post, this post being designated 22'. It will be noticed from an inspection of this figure of the drawings that the foot of this post is slightly pointed and rests on the deck board below. In wrecking this construction it is a simple matter to merely loosen the post and lift it out of the concrete entirely due to its pointed end.

It will be seen from the foregoing that the girder forms employed by me are suspended intermediate their ends and so braced that relative movement between the forms is prevented, this bracing also preventing swaying of the entire panel structure. It will be seen also that the deck is supported principally by the girder forms, only four supporting posts being employed in my construction, as illustrated. This, of course, is of great advantage over that form of construction wherein supporting posts are employed at fairly close intervals throughout the extent of the panel as well as beneath the girder forms themselves and permits the various trades to install their apparatus after the forms have been erected. It will be seen also that throughout my improved construction I employ short lengths or sections of materials, thereby reducing the cost of handling the same inasmuch as less labor is required for handling these materials and also reducing the danger or liability of injury to the floor below when the forms are wrecked. It will be seen also that by my improved construction I am able to build up the forms in tiers, permitting any number of tiers to be installed without regard to whether the concrete at each form has been poured or not. It will be apparent also that by my improved construction, whether the forms are built in tiers or not, it is feasible to install the girder forms as fast as the steel work is erected, thereby enabling the form work to keep abreast of the steel work at all times.

While I have described a specific embodiment of my invention it is to be understood that the same may be changed in its details without, however, departing from the spirit and scope of this invention.

What I claim is:

1. In a girder form construction, the combination of clamps or end supports attached to the columns spanned by the girders, intermediate supports suspended from the girders at points intermediate their ends and sectional soffit and haunch members carried by said end and intermediate supports and lateral braces for the soffit and haunch members detachably secured to said intermediate supports, substantially as described.

2. In a girder form construction, the combination of end and intermediate supports for the girder forms, said intermediate supports being suspended from the girders at points intermediate their ends, the girder forms comprising sectional soffit and haunch boards carried by said end and intermediate supports, and lateral braces for the soffit and haunch boards detachably secured to the lower portions of the girder forms at points intermediate their ends, substantially as described. 70
5. In a form structure, the combination of four girder forms bounding a bay or panel, end supports for said girder forms, diagonal supports for the girder forms suspended from the girders and extending beneath the forms at points intermediate their ends, and lateral braces for the girder forms extending diagonally of the bay or panel and detachably secured to said diagonal supports, substantially as described. 75
10. In a form structure, the combination of four girder forms bounding a bay or panel, end supports for said girder forms, diagonal supports for the girder forms suspended from the girders and extending beneath the forms at points intermediate their ends, and lateral braces for the girder forms extending diagonally of the bay or panel and detachably secured to said diagonal supports, substantially as described. 80
15. In a form structure, the combination of four girder forms bounding a bay or panel, end supports for said girder forms, diagonal supports for the girder forms suspended from the girders and extending beneath the forms at points intermediate their ends, and lateral braces for the girder forms extending diagonally of the bay or panel and detachably secured to said diagonal supports, substantially as described. 85
20. In a form structure, the combination of four girder forms bounding a bay or panel, end supports for said girder forms, diagonal supports for the girder forms suspended from the girders and extending beneath the forms at points intermediate their ends, and lateral braces for the girder forms extending diagonally of the bay or panel and detachably secured to said diagonal supports, substantially as described. 90
25. In a form structure, the combination of four girder forms bounding a bay or panel, stirrups carried by the haunches of two opposite girder forms, form girders supported by said stirrups, ledger members secured to the haunches of the other two girder forms, joist sections each having one end supported by said ledgers and the other end by said form girders, and a panel deck supported by said joints. 95
30. In a form structure, the combination of four girder forms bounding a bay or panel, supporting posts for the central portion of the bay, cap plates joining the upper ends of said posts, deck girders extending transversely of the bay and each comprising overlapping sections, the outer ends of said deck girders being detachably supported upon the sides of said girder forms and the intermediate overlapping ends thereof being supported by said cap plates, and a deck carried by said deck girders, substantially as described. 100
35. In a form structure, the combination of four girder forms bounding a bay or panel, supporting posts for the central portion of the bay, cap plates joining the upper ends of said posts, deck girders extending transversely of the bay and each comprising overlapping sections, the outer ends of said deck girders being detachably supported upon the sides of said girder forms and the intermediate overlapping ends thereof being supported by said cap plates, and a deck carried by said deck girders, substantially as described. 105
40. In a form structure for panels or bays, the combination of four girder forms bounding the bay or panel, a supporting upright for the center of the bay structure, deck girders comprising overlapping sections having their outer ends supported on the girder forms and their overlapping inner ends on said upright, deck joists comprising overlapping sections having their outer ends supported on the girder forms and their inner ends on the deck girders, and sectional deck boards secured to said joists, substantially as described. 110
45. In a form structure for panels or bays, the combination of four girder forms bounding the bay or panel, a supporting upright for the center of the bay structure, deck girders comprising overlapping sections having their outer ends supported on the girder forms and their overlapping inner ends on said upright, deck joists comprising overlapping sections having their outer ends supported on the girder forms and their inner ends on the deck girders, and sectional deck boards secured to said joists, substantially as described. 115
50. In combination in a form structure for column supported girders, forms for said girders, end and intermediate supports for said forms, said intermediate supports being suspended from said girders, lateral braces for the girder forms detachably secured to said intermediate supports and a deck structure composed of overlapping girder and 120
55. In combination in a form structure for column supported girders, forms for said girders, end and intermediate supports for said forms, said intermediate supports being suspended from said girders, lateral braces for the girder forms detachably secured to said intermediate supports and a deck structure composed of overlapping girder and 125
60. In combination in a form structure for column supported girders, forms for said girders, end and intermediate supports for said forms, said intermediate supports being suspended from said girders, lateral braces for the girder forms detachably secured to said intermediate supports and a deck structure composed of overlapping girder and 130
